UNITED STATES PATENT OFFICE.

FRANK D. SMALL, OF WEST PARIS, MAINE.

COLLAR-BUTTON.

No 868,716.

Specification of Letters Patent.

Patented Oct. 22, 1907.

Application filed October 19, 1905. Serial No. 283,491.

To all whom it may concern:

Be it known that I, FRANK D. SMALL, a citizen of the United States, residing at West Paris, in the county of Oxford, in the State of Maine, have invented a useful Improvement in Collar-Buttons, of which the following is a specification.

My invention relates to certain new and useful improvements in collar buttons, and has for its object to provide a button that is very simple and cheap in construction and one that is effective in use.

With these objects in view my invention consists of the novel construction and arrangement of parts hereinafter described, pointed out in the claims and shown in the accompanying drawing in which;

- 15 Figure 1 is a perspective view of my improved button. Fig. 2 is a vertical sectional view. Fig. 3 is a bottom plan view. Fig. 4 is a perspective view of the head. Fig. 5 is a perspective view of the shoe. Fig. 6 is an enlarged sectional view of the shoe.
- 20 Referring to the drawing A indicates the shoe of the button which is provided with a tubular shank B, having wings B' which are adapted to pass through the button hole and prevent the shoe from turning. The shank B is provided with an inwardly projecting flange B², adjacent its lower end the under side of which is formed with oppositely arranged raised portions having beveled sides. These portions are arranged at right angles to the wings of the shank and are provided with grooves B³, for the purpose hereinafter described.
- 25 30 The head C is of the same width as the shank B but

is formed with elongated turned down ends C' which are adapted to be turned cross-wise of the button hole after passing through and securely hold the same in place. A solid shank C³ is formed integral with the circular shoulder C² of the head and is adapted to fit 35 within the tubular shank and extend past the flange B² and to be securely locked therein by a pin C⁴ which is adapted to fit within the grooves B³ and lock the head C in a cross-wise position. A coil spring D surrounds the solid shank C³ in the tubular shank and 40 has the tendency to throw the head outwardly and to securely hold the pin in the grooves.

Having thus described my invention, what I claim and desire to secure by Letters Patent is:

In a collar button, the combination with a shoe having 45 a central opening provided with an upwardly extending tubular shank having oppositely disposed wings, of an inwardly projecting annular flange formed in said shank adjacent the lower end on a plane above the shoe, said flange having oppositely arranged raised portions provided 50 with central grooves and beveled sides on its under side, two of said grooves being parallel with the wings of the shank, an elongated head provided with a shoulder having a solid shank adapted to fit in said tubular shank, a pin 55 secured in the ends of said shank adapted to fit in the grooves of the flange said pin being parallel with the elongated head and a coiled spring arranged on said shank between the shoulder of the head and the flange of the tubular shank, for the purpose described.

FRANK D. SMALL.
